United States Patent

Des. 237,632
Patented Nov. 11, 1975

237,632

SAMPLE COLLECTOR OR OTHER SIMILAR ARTICLE

Louis Franklin Lederer, Lincoln, Nebr., assignor to
Instrumentation Specialties Company

Filed Jan. 2, 1974, Ser. No. 429,508

Term of patent 14 years

Int. Cl. D24—02

U.S. Cl. D32—2 B

FIG. 1

FIG. 2

FIG. 4

FIG. 3

FIG. 1 is a perspective view of a sample collector or other similar article showing my new design;

FIG. 2 is a top plan view thereof;

FIG. 3 is a bottom plan view thereof; and

FIG. 4 is an exploded view thereof.

I claim:

The ornamental design for a sample collector or other similar article, substantially as shown.
